UNITED STATES PATENT OFFICE.

GEORGE KUPEC AND JOHN SLOSAR, OF NEW SALEM, PENNSYLVANIA.

FLYING-BOMB.

1,276,547.

Specification of Letters Patent. Patented Aug. 20, 1918.

Application filed September 26, 1917. Serial No. 193,238.

To all whom it may concern:

Be it known that we, GEORGE KUPEC and JOHN SLOSAR, subjects of the King of Hungary, residing at New Salem, in the county 5 of Fayette and State of Pennsylvania, have invented certain new and useful Improvements in Flying-Bombs, of which the following is a specification.

This invention relates to certain new and 10 useful improvements in flying bombs.

The primary object of the invention is the provision of a bomb especially adapted to be dropped from aeroplanes and arranged with a plurality of means for insuring the 15 exploding thereof.

A further object of the invention is the provision of a bomb adapted for explosion upon striking an object and being arranged for maintaining an upright position during 20 its travel through the air, a plurality of explosion chambers being arranged adapted for simultaneous operation.

In the drawings forming a part of this application and in which like numerals refer 25 to corresponding parts throughout the several views,

Figure 1 is a side elevation of the device with parts broken away.

Fig. 2 is a top plan view thereof and 30

Fig. 3 is a horizontal transverse sectional view taken upon line III—III of Fig. 1.

The device herein illustrated may be projected in any desired manner such as by dropping from an aeroplane and broadly 35 consists of a main bomb or exploding member 10 of inverted conical form arranged at the bottom of the device and having auxiliary explosive members 11 mounted in cruciform arrangement thereon by being attached 40 to a post 12 centrally mounted upon the top or base side of the explosive member 13.

The base member 10 has a removable lower end 14 at the apex thereof for positioning a plug 15 within the base member arranged 45 with a fire pin 16 downwardly projecting through the pointed end of the cap. A partition is arranged within the member 10 having a central opening 17 through which the gun cotton, dynamite or other explosive material 18 is positioned within the explosion chamber 19 of said member 10.

A percussion cap 20 is arranged adjacent the perforation 17 adapted to be engaged by the pointed inner end 21 of the

plug 15 when the pin 16 is violently contacted when the device strikes an object, it being noted that a spring 22 is arranged between the plug 15 and the partition 16 for normally maintaining the point 21 out of contact with the cap 20.

The auxiliary explosion members 11 are in the form of casings being removable top closures 23 for filling said members with gun cotton or other explosive material 24. Firing rods 25 are obliquely positioned through the 65 base member 10 having their lower ends engaging a shoulder 26 of the plug 15 while the upper end portions of the rods 25 pass through stuffing box 27 arranged in the bottoms of the casings 11 and are preferably 70 arranged with springs 28 for normally maintaining the pointed upper free end 29 of the said rods spaced from percussion or ignition caps 30 carried within perforated lugs 31 within the explosive contents 24 of said auxiliary explosive members.

The operation of the device will be apparent from this description thereof as the striking of the pin 16 upon any object will force the plug 15 inwardly for exploding 80 the cap 17 and igniting the base member 10 for exploding its contents 18 while such movement of the plug will simultaneously elevate the rods 25 forcing the points 29 of the rods in contact with the caps 30 and 85 exploding the caps for firing the contents 24 of the auxiliary explosive members 11. In this manner, the explosion of the bomb is insured as one or more of the explosive chambers will be fired upon dropping the 90 device so that the firing pin 16 comes in violent contact with some object while the form of the device is adapted to maintain the base member 10 at the bottom thereof during the movement of the device through the air 95 while the radially projecting members 11 assist in maintaining a travel thereof in a uniform direction.

What we claim as new is:—

A bomb comprising a hollow inverted 100 conical base member, a post upon said member, radially projecting casings carried by the said post, explosive material within the said casings and base, ignition caps for the explosive material of said casings and base 105 member, a shiftable plug at the apex of said base member, a downwardly projecting firing pin carried by said plug extending out-

wardly of the base member, a point upon said plug adapted for engaging the cap carried by the base member, firing rods having their lower ends engaging the said plug and their upper ends pointed and normally arranged spaced from the caps of said explosion casings whereby all of the said caps

are adapted for simultaneous operation upon the inward movement of the said firing pin when the device strikes an object.

In testimony whereof we affix our signatures.

GEORGE KUPEC.
JOHN SLOSAR.
